FIG. 1.

FIG. 2.

INVENTOR

JOHN R. SUTTON

BY *Rodney Redell*
ATTORNEY

UNITED STATES PATENT OFFICE

115,866

DESIGN FOR A SHOE

John R. Sutton, St. Louis, Mo., assignor to Johnson, Stephens and Shinkle Shoe Company, St. Louis, Mo., a corporation of Missouri

Application June 19, 1939, Serial No. 85,569

Term of patent 3½ years

To all whom it may concern:

Be it known that I, John R. Sutton, a citizen of the United States, residing at St. Louis, Missouri, have invented a new, original, and ornamental Design for Shoes, of which the following is a specification, reference being had to the accompanying drawing, forming part thereof.

Figure 1 is a perspective view of the shoe; and

Figure 2 is a transverse section taken approximately on the line 2—2 of Figure 1.

The design is characterized by the vamp and

rear quarter constituting spaced parts of the shoe upper and presenting a substantially smooth appearance while the remainder of the upper including a part above the vamp and between the vamp and the rear quarter and extending downwardly to the sole presents the appearance of a series of small puffs.

I claim:

The ornamental design for a shoe, substantially as shown and described.

JOHN R. SUTTON.
